UNITED STATES PATENT OFFICE.

JAMES CHRISTY, OF CLEVELAND, OHIO, ASSIGNOR TO THE PORTAGE RUBBER COMPANY,
OF AKRON, OHIO, A CORPORATION.

DESIGN FOR A VEHICLE-TIRE.

46,942.

Specification for Design.

Patented Feb. 16, 1915.

Application filed November 30, 1914. Serial No. 874,947. Term of patent 14 years.

To all whom it may concern:

Be it known that I, JAMES CHRISTY, a citizen of the United States, residing at Cleveland, county of Cuyahoga, and State of Ohio, have invented a new, original, and ornamental Design for a Vehicle-Tire, of which the following is a specification, reference being had to the accompanying drawing, forming part thereof.

Figure 1 is a perspective view of the tire on a reduced scale showing my new design,

and Fig. 2 is an elevation of a portion thereof of approximately full size. Fig. 3 is a cross section of the tire.

I claim:

The ornamental design for a vehicle tire, as shown.

JAMES CHRISTY.
